(57) CLAIM

The ornamental design for a refill for volatile dispenser, as shown and described.

DESCRIPTION

FIG. 1 is a left, top, rear perspective view of a refill for volatile dispenser embodying our new design;

FIG. 2 is a right, top, frontal perspective view thereof;

FIG. 3 is a front elevational view thereof;

FIG. 4 is a right side elevational view thereof;

FIG. 5 is a left side elevational view thereof;

FIG. 6 is a top plan view thereof;

FIG. 7 is a bottom plan view thereof; and,

FIG. 8 is a rear elevational view thereof.

The broken line representations in the views are for illustrative purposes only and form no part of the claimed design.

In a preferred embodiment the nature of this product is a refill for an air treatment dispenser suitable to hang on a person's belt, pocket, or other clothing item and dispense insect repellents from the refill (for example, mosquito repellent).
